UNITED STATES PATENT OFFICE.

JOHN R. GRUNDY, OF PHILADELPHIA, PENNSYLVANIA.

FLEXIBLE COUPLING.

1,352,953.

Specification of Letters Patent. Patented Sept. 14, 1920.

Application filed October 30, 1919. Serial No. 334,519.

To all whom it may concern:

Be it known that I, JOHN R. GRUNDY, a citizen of the United States, residing in Philadelphia, Pennsylvania, have invented 5 Flexible Couplings, of which the following is a specification.

One object of this invention is to provide a device for coupling the adjacent ends of two shafts which shall be of such a nature 10 that it shall be capable of transmitting power from one of them to the other, even though they be out of alinement and have a greater or less degree of relative longitudinal movement;—the invention more particularly 15 contemplating a form of coupling including two shaft-carried members and an intermediate member, of which the former are of such construction and so engage the latter as to prevent the separation of the coupling elements under operating conditions.

Another object of my invention is to provide a flexible shaft coupling which shall be simple, substantial and compact in construction and in which the shaft-carried elements 25 while normally so engaging an intermediate element as to prevent longitudinal separation of the coupling elements, shall at the same time be of such form and construction as to permit of the quick and convenient assembly 30 or separation of said elements.

These objects and other advantageous ends I attain as hereinafter set forth, reference being had to the accompanying drawings, in which,

35 Figure 1 is a side elevation of a flexible shaft coupling constructed in accordance with my invention;

Fig. 2 is a detached perspective view illustrating the detail construction of the elements 40 of the coupling shown in Fig. 1; and

Figs. 3 and 4 are respectively a front and a side elevation of a slightly modified form of the shaft-carried elements.

In the above drawings 1—1 represent the 45 two shaft-carried elements of my invention which are both of the same form and construction, and 2 represents the intermediate member whereby said first members are operatively connected and through which power is transmitted from one to the other.

Each of the elements 1 consists of a sleeve or collar 4 designed to be keyed or otherwise rigidly mounted on one of two shafts to be connected and has formed integral 50 with it two oppositely extending arms 3—3.

Each of these arms adjacent its end has

fixed to or formed integral with it a substantially rectangular block 5 projecting from the outer portion of its outer face and the two blocks 5 of each arm are equi-distant 60 from the center line of the sleeve 4 as well as in line with each other, having in that form of my invention shown in Figs. 1 and 2, integral retaining plates 6 mounted on their outer faces and projecting beyond their 65 sides. As shown at 6^a in Figs. 3 and 4, these retaining plates may be removably connected to the blocks 5 as by screws 7, and may be of the same radial width as said blocks, although in that form of my invention 70 shown in Figs. 1 and 2 these plates are of less width than that of the blocks on which they are mounted, as well as placed at the outer ends of said blocks.

The intermediate member 2 consists of a 75 disk of material, such as leather, having the quality of absorbing or cushioning shocks, although obviously it may be made of material such as vulcanized fiber possessing said quality in a lesser degree. This disk is 80 formed with two sets of oppositely placed radially extending recesses 8—8 and 9—9 preferably at right angles to each other and of a width sufficient to snugly though slidably receive the aligned blocks 5—5 of the 85 two shaft-carried elements 1—1 respectively. The depth of these slots is materially greater than the length of the blocks 5 so that in the form of my invention shown in Figs. 1 and 2, when the intermediate member 90 2 is inclined at an angle to the plane of the arms 3 of one of the elements 1 and the lower of the blocks 5 of one of the latter is entered in the lower one of the recesses 9, the opposite side of said intermediate element 95 will just pass under the projecting ends of the upper plate 6, thereby making it possible to bring the intermediate member into a position parallel with the arms 3 and cause the second of the blocks 5 to enter the upper 100 recess 9.

Under these conditions the intermediate member is freely slidable across the outer face of the arms 3 and is guided by the blocks 5 thereon although, except in the position above noted, it is held in place by the projecting ends of the plates 6;—the blocks 5 having a height equal to the thickness of the intermediate member 2.

The second of the shaft-carried members 110 1 is applied to the intermediate member 2 in the manner above described, except that

its blocks 5 are successively inserted in the recesses 8 so that its arms 3 extend in lines at right angles to the similar arms of the other shaft-carried member. Under conditions of use power is transmitted from the blocks of one of the members 1 to the sides of one pair of the segmental portions of the intermediate member 2 formed or defined by the radial slots 8 and 9, and is transmitted through these segments to the similar blocks 5 of the shaft-carried members 1.

Obviously any shock due to sudden increase in the load on the driven shaft will be absorbed or cushioned by the intermediate member 2 and by reason of the more or less loose connection of this with the members 1, it is possible for the two shafts connected to the latter to be continuously operated even though they should be out of alignment. The construction illustrated also permits of a limited longitudinal movement of the members 1—1 toward and from each other and the coupling elements are prevented from separating to an objectionable extent by reason of the overhanging ends of the plates 6 which engage the intermediate member 2. Owing to the lateral flexibility of the latter member, it will yield to a limited extent without injury in response to a force tending to separate the members 1.

In that form of my invention shown in Figs. 3 and 4 I form each of the shaft-carried elements with disk like flanges 3^a instead of arms 3—3 and indent or recess the

adjacent faces of each of them for the reception of the retaining plates 6 of the blocks on the other. This construction is safer, having fewer projecting corners or edges than that of Figs. 1 and 2 and consequently is less liable to catch on or become entangled with adjacent objects.

I claim:

1. A flexible coupling consisting of two shaft-carried elements each including radially extending portions having outwardly projecting blocks on their adjacent faces; and an intermediate cushioning member in the form of a substantially flat plate having recesses for the reception of the blocks of said members, each of said blocks having a head overhanging the adjacent face of the intermediate member.

2. A shaft coupling consisting of two shaft-carried elements each having portions projecting in opposite directions from and at right angles to the center line of the shaft upon which it is mounted; flat sided blocks projecting from said portions; integral heads mounted on the outer faces of said blocks so as to overhang the sides of the same; with an intermediate member having two sets of radial recesses extending in lines substantially at right angles to each other and formed for slidably receiving the blocks of the two shaft-carried members.

In witness whereof I affix my signature.

JOHN R. GRUNDY.
